ATTORNEY

UNITED STATES PATENT OFFICE

THOMAS I. POTTER, OF PORTLAND, OREGON

STRUCTURAL TOY

Application filed April 18, 1927. Serial No. 184,670.

This invention relates generally to the art of toy making, and particularly to structural elements whereby various devices can be constructed from standard parts by varying the manner in which they are assembled.

The main object of this invention is to provide a special form of structural element by means of which various constructions can be assembled or taken down in a relatively short

10 space of time by a child or unskilled person.

The second object is to provide a structural element which can be assembled or united with other elements by merely pressing same together with the fingers, and the connection made will be extremely secure and at the same time permit of angular movement and the subsequent separation of the parts without the use of tools of any kind.

The third object is to provide a special form of joint whereby various structural elements can be joined together without the aid of separate parts such as bolts, nuts, pins or other separate elements.

The fourth object is to encourage the assembling of the various parts into different combinations by merely reducing the amount of labor and patience required for such operations, thereby adding to the experience and training afforded the user by means of such devices.

It is a well known fact that while various types of structural elements are now on the market in which the assembling is preferably made by means of small bolts and nuts that such assembling, even on a moderate scale, is sufficient to try the patience of an adult, which is much more the case with a younger person, who, having sustained his interest sufficiently to assemble the parts of an interesting and possibly ingenious device will not be apt to pick it apart and re-assemble it in a new combination on account of the labor involved.

It is to overcome these objections that the device described in the following specification has been constructed, as illustrated in the accompanying drawing, in which:

Figure 1 is a plan of a long flat unit. Figure 2 is a similar view of a shorter unit and

50 Figure 3 is a similar view of a still shorter

unit. Figure 4 is a perspective view of an angular section equipped with the special joint forming elements. Figure 5 is an enlarged section through the joint and an attached part. Figure 6 is a transverse section taken along the line 6-6 in Figure 5. Figure 7 is a perspective view showing a form of element not requiring the special joint connections. Figure 8 is a similar element in which the special joints are employed. Figure 9 is a perspective view of an angular element. Figure 10 is a fragmentary view in enlarged perspective showing several of the units fastened together with one portion broken away showing how two perforated parts can be mounted on one flanged fastening. Figure 11 is a plan of the element 11 shown in Figure 7. Figure 12 is a view of the smallest unit embodying only a single fastener.

Similar numbers of reference refer to similar parts throughout the several views.

Referring in detail to the drawing, it will be seen that there is illustrated several representative types of elements which may have no end of variations for length, breadth, thickness or cross section. Only a few of the representative forms are shown as these are sufficient to convey the idea involved.

Briefly, the invention resides in using flat steel members which are united at their points of intersection by snap fasteners preferably integral or permanently attached to one or the other of the intersecting pieces.

In practice it is preferable to alternately form round holes and fasteners along the length of a section, although, of course, other pieces having all fasteners or all open holes can be conveniently employed.

In Figure 7 is shown a relatively short flat link 11 provided with round openings 12 and rounded ends 13. In Figure 8 is shown a small element but with fastener elements at each end. Each fastener element consists of a flanged opening 14 whose opposite sides 15 are inturned toward each other, the inturned portions projecting slightly beyond the flange 14 and separated therefrom by the slits 16, which supply the desired resiliency to the fastener.

It is also preferable to undercut the exteriors of the members 15 in order that they shall more securely hold an associated member by passing through its circular hole 12.

It will be noted that in Figure 1 a long element 17 is shown and in Figure 2 a shorter element 18 is illustrated, whereas in Figure 3 a still smaller element 19 is shown. In Figure 4 an angular element 20 is illustrated with its fasteners on the inner side of the angle, although this is not necessarily the case. In Figure 9 is shown an angular element 21 having only two connections, one a hole 12 and the other a fastener (above described). Figure 11 is shown close to the member 17 for the purpose of illustrating the fact that its openings 12 are spaced differently than in the members containing fasteners, since the elements having only the holes 12 are commonly employed only as braces or diagonal members.

In Figure 10 are included other elements such as a shaft 22, a crank 23, a pulley 24 and operating line 25 such as are commonly found in toys of this nature.

In Figure 12 is shown a single fastener 26 whose flanged portion 15 is of any desired length for the purpose of uniting two or more plates together. In other words, the member 26 is a separate fastening unit instead of being integral with either of the joined plates. By means of the unit 26 a number of elements (such as are shown in Figure 7 for instance) can be easily joined together.

While the circular shape of flange 14 is preferable in most instances, this member can be made square or assume other shapes outside of that illustrated, for the purpose of preventing the relative movement of the associated parts without the employment of braces, as indicated in dotted lines in Figure 6.

The element 11, as shown in Figures 7 and 11, may either be spaced similarly to the openings 12 and the flanged openings 14, or they may be spaced to distances equaling the hypotenuse formed by perpendicularly intersecting bars 17 between a pair of flanged openings 14 immediately adjacent to the point of intersection, or other related points of fastening. In other words—if all of the openings and fastenings were equi-distantly spaced it would be impossible to use diagonal braces for holding other parts perpendicular to each other, but this objection is overcome by providing certain members 11 with increased spacings, as suggested.

I am aware that many forms of structural elements have been made in the past; I therefore do not claim such devices broadly but intend to cover only such forms and modifications thereof in which snap fasteners are employed as set forth in the appended claims.

I claim:

1. A snap fastener for flat metal structural units consisting of a flanged projection

formed in one member, said flange having diametrically opposed parts thereof projecting therefrom beyond its flange and inturning toward each other, the outer portions which project beyond said flange extending outside of the periphery of said flange in a manner to be compressed when a perforated part is placed upon said flanged projection and then to urge said perforated part against said flanged projection bearing member.

2. A snap fastener for joining two sheet metal structural units consisting of one perforated member and one snap bearing member, said snap consisting of a flanged opening the flange of which is adapted to enter the perforation in said first mentioned member, said flange having parallel slits formed therein extending into the flat portion of the member itself for the purpose of forming springs in the side of said flange, the material between said slits forming projecting areas extending beyond the end of said flange and then inturning toward each other and the outer portion of said projecting areas extending outside of said flange to form a spring retainer for the perforated part.

THOMAS I. POTTER.
